HEAT-TREATING FURNACE

Willard Roth, Meadville, and Thomas L. Case, West Mead Township, Crawford County, Pa., assignors, by mesne assignments, to Sunbeam Equipment Corporation, a corporation of Delaware

Application January 27, 1956, Serial No. 561,780

7 Claims. (Cl. 266—3)

Our invention relates generally to temperature-treatment chambers, and it has more particular relation to a furnace for the heat-treatment of a strip of aluminum or the like, which is continuously passing through the furnace. The furnace or other chamber may consist of either one, and preferably both, of two parts, namely a first part which acts as a heat-exchanger for heating (or cooling) the strip, soon after it enters the furnace, until the strip reaches a predetermined desired temperature, and a second part for "soaking" the strip at substantially this predetermined temperature for a predetermined length of time, which is determined by the length of the strip which is included in the soaking-chamber at any moment, and the velocity of the strip.

When the strip is aluminum, it is desirable to "soak" the strip at a temperature which is of the order of 975° F., more or less, in a heat-treatment soaking-chamber in which the temperature of the strip is maintained constant within extremely close limits, such as from 2 to 5° F. Usually, the aluminum strip enters the furnace at a temperature which is not quite as high as the desired heat-treatment or soaking-temperature, and in this case the furnace is provided with a special heating-section wherein the temperature of the strip is raised as quickly as possible to the desired soaking-temperature.

There are problems which have had to be solved in both parts of the furnace.

The strip to be temperature-treated does not need to be aluminum, and it could conceivably require refrigeration, rather than heating, with respect to the temperature of the ambient atmosphere outside of the chamber. In its most general sense, therefore, our invention may be regarded as being a heat-exchanging device, or a temperature-holding device, or both, without limitation as to whether the holding-temperature is above or below that of the ambient atmosphere, although the invention was particularly designed for the heat-treatment of an aluminum strip, and our description will be directed more particularly to the embodiment of our invention in the form of a furnace rather than a refrigerator.

The main features of our invention will be pointed out more particularly hereinafter. Two alternative forms of embodiment are shown in the drawings, wherein—

Figure 1 is a vertical longitudinal sectional view of a vertical three-pass aluminum-strip furnace, on the section-plane I—I of Fig. 2;

Fig. 2 is a view, partly in side-elevation, and partly in vertical section on a plane indicated by the line II—II in Fig. 1;

Fig. 3 is a front elevational view of the upper part of the furnace of Figs. 1 and 2, as would be seen from the plane III—III in Fig. 2;

Figs. 4 and 5 are sectional views on the planes IV—IV and V—V, respectively, as indicated in Figs. 2 and 3; and

Figs. 6 and 7 are sectional views, similar to Figs. 1 and 2, showing a somewhat modified form of construction, in the form of a vertical twelve-pass aluminum-strip furnace, the sectional planes being indicated by the lines

2

VI—VI of Fig. 7 and VII—VII of Fig. 6, respectively.

The furnace which is shown in Figs. 1 to 5 has a tall heat-insulated furnace-housing 10 which is supported on a base-framework 11, and which is free to expand and contract vertically between suitable vertical guides 12. The housing 10, in this form of construction, has an entry-slit 13 which is located at the top, and an egress-slit 14 which is located at the bottom, the housing being otherwise as gas-tight as it can conveniently be made.

10 The furnace is provided with a means for guiding a longitudinally moving strip 15 in one or more long substantially unsupported vertical spans or passes, as the strip moves through the furnace from the entry-slit 13 to the egress-slit 14. In Fig. 1, three passes of the strip 15 are shown, as provided by a lower roll or roller 16 between the first and second passes, and an upper roll or roller 17 between the second and third passes. The two rollers 16 and 17 may be driven by suitably controlled motors 16' and 17', as shown in Fig. 2. Both rollers are 20 journal-supported outside of the furnace, where accurate alignment may be more easily maintained, out of the heat of the furnace, by means of bearings 18.

In the illustrated form of embodiment, as shown in Figs. 1 and 2, both of the rollers 16 and 17 are removable 25 for repair and replacement. To this end, their bearings 18 are carried by pivoted arms 19 which are counterweighted at 20, as shown in Fig. 1. In order to prevent any substantial chimney-action within the furnace-housing, the roll-shafts are sealed reasonably tightly through spring-loaded friction-sealing means 22 (Fig. 1). The rolls can be removed from the furnace through movable or removable insulated plugs 23 and 24 in the bottom and top, respectively, of the furnace-housing 10. The bottom roller 16 may be used as a tension-adjuster roller, which 30 can move slightly up and down to control the tension of the strip when the strip is being initially heated, and the variation in the length of the strip can be communicated to a suitable control or indicating device 25 which is attached to the counterweight 20 of this lower roller 16.

The aluminum strip 15 will usually enter the entry-slit 13 of the furnace-housing 10 in Fig. 1 at a certain temperature, say 925 or 950° F., which is a little below the intended soaking-temperature, which is usually 975° F. During the first 15% (more or less) of the strip-travel in the furnace, the strip is heated so as to bring it up precisely to the desired soaking-temperature. Our furnace is a recirculating convection-heating furnace, and so this initial heating of the strip, to bring it fully up to temperature, is accomplished by means of a narrow elongated vertically disposed heat-exchanging passageway 30 (Fig. 1), which is suspended within the furnace close to the entry-slit 13, so that the first span or pass of the strip passes approximately centrally through this passageway, the walls of the passageway being closely spaced from the 55 side surfaces and the edges of the strip 15.

We provide a gas-recirculating system for maintaining a supply of gas at a temperature which is hotter than the entrance-temperature of the strip (assuming that the strip is to be heated), and we supply this gas through a suitable inlet-duct or ducts 32 (Fig. 2) to a plenum chamber 33 (Fig. 1) at the top of the heating-passageway 30. In the particular form of embodiment of the invention which is shown in Fig. 1, the hot gas in the plenum chamber 33 is divided into two parts. Approximately 65 half of the gas is bled off at the top and fed diagonally downwardly in two substantially equal heat-exchanging streams 34 of gas, which flow longitudinally along the respective surfaces of the strip 15 in said heating-passageway 30. In the form of invention which is shown in Fig. 1, the other half or portion of the hot gas in the plenum chamber 33 is fed downwardly into two hot-gas

passages 35 which are disposed on the opposite sides of the heating-passageway 30. From these two hot-gas passages 35, we admit a plurality of pairs of equal and opposite downwardly directed streams 36 of gas which superimpose, on the respective longitudinally moving heat-exchanging streams 34, substantially equal and opposite lateral converging movements of said gas, which impinge upon the opposite surfaces of the strip 15, at each of a plurality of levels in the vertical path of the strip as it passes downwardly through the heating-passageway 30.

The purposes of the laterally impinging streams 36 is mainly to provide a centering force for holding the strip 15 approximately in the center of the long narrow heating-passageway 30. There may be many reasons which might tend to cause, or contribute to, the flapping or decentering of the strip as it passes through the narrow heat-exchanging passageway 30. For one thing, the length of the unsupported span of the strip 15 is fairly great, being of the order of seventy feet, in the furnace which is shown in Fig. 1, so that a relatively slight disturbance may induce or initiate flapping or lateral movement of such a long strip. In the second place, the longitudinal or vertical velocity of the two streams 34 of the hot gas is quite high, being, for example, of the order of from 100 to 200 feet per second (more or less) in the furnace of Fig. 1, and the laws of gas-flow may contribute toward the creation of sensible laterally-applied strip-moving forces at such velocities. In the third place, the strip 15 itself is not absolutely uniform in width or in gauge or in flatness, being subject to certain random warpings which may contribute considerably toward the initiation of a deleterious flapping or decentering of the strip, if this decentering tendency were not overcome by the centering action which is obtained by the laterally impinging gas-movements 36, preferably arranged in equal and opposite pairs, so that, if the strip became decentered or off-centered, the strip would get further away from one lateral stream and closer to the other lateral stream, thus resulting in a centering action, because the impinging force of each lateral stream diminishes as the strip gets further away from the stream-source.

We are not limited, of course, to the particular means which is shown in Fig. 1 for producing these laterally-directed strip-centering gas-movements 36 at one or more points or levels within the strip-heating passageway 30. Besides the strip-centering action of the lateral streams or gas-movements 36 within the narrow heating-passageway 30, these lateral streams are also useful in causing the hot gas to impinge in good heat-exchanging relation to the surfaces of the strip 15, increasing the turbulence of the gas within the heating-passageway 30, thus increasing the rate of heat-exchange between the gas and the strip.

The major portion or volume of the space within the furnace-housing 10 of Fig. 1 is a heat-soaking space, which is entered by the strip 15 as it emerges from the bottom of the heating-passageway 30 at the desired temperature at which the strip is to be "soaked" or held, for a matter of four minutes, or whatever other time is prescribed by the metallurgists for the heat-treatment of the aluminum strip. In the furnace which is shown in Fig. 1, it was specified, by the aluminum-strip manufacturer, that the strip should be held at a constant soaking-temperature within such narrow temperature-limits that it at first seemed impossible to satisfy such strict conditions.

These strict soaking-temperature limits (amounting to something like ± 2 or 3° F.), are met in our present invention by providing a long open-ended tubular heat-insulated baffle 40, which is disposed in a substantially vertical position within the heat-insulated furnace-housing 10, in closely spaced relation to the four side walls of the housing. Within this baffle 40 are disposed the

lower portion of the first span or pass of the strip 15 (after it leaves the heating-passageway 30), and all of the second and third spans or passes of said strip. The lower roller 16 is disposed below the bottom open end of the baffle 40, and the upper roller 17 is disposed above the upper open end of said baffle 40, while the emerging portion of the strip 15 extends down below the lower end of the baffle, and comes out of the egress-slit 14 in the housing 10.

10 The hot gas emerges from the bottom of the narrow heating-passageway 30 at a temperature which is approximately the same as the desired soaking-temperature of the strip, within the previously specified narrow limits. It is necessary to provide a means for guiding this exit-gas, which leaves the heating-passageway 30, so that most of this exit-gas travels longitudinally in slow-moving temperature-soaking streams 41 on opposite sides of the remaining portions of the entire length of the strip within the temperature-soaking space within the baffle 40. In the form of invention shown in Fig. 1 this temperature-soaking gas-flow, between the first and second passes of the strip 15, is secured by means of a partition 42 (Fig. 1), which is suspended from the lower inner edge of the hot-gas passage 35 of the heating-passageway 30.

15 As a result of the foregoing construction, one stream 41A of the exit-gas leaves the heating-passageway 30 in the space between the adjacent side-wall of the baffle 40 and the nearby surface of the first pass of the strip 15, as shown in Fig. 1. This stream 41A thus passes downwardly to the space 43 below the open bottom end of the baffle 40. A second stream 41B of this exit-gas flows downwardly from the heating-passageway 30 between the other side of the first pass of the strip 15 and the partition 42, discharging at or near the lower open end of the baffle 40. From the lower end of the baffle 40, in the space 43 therebelow, the hot gas spreads out across the entire area of the bottom portion of the furnace-housing 10, and passes up in four upwardly moving streams 41C to 41F on opposite sides of the second and third passes of the strip 15, discharging therefrom in the space 44 above of the open top end of the baffle 40.

20 According to our invention, as large a portion of the hot gas as may be necessary is diverted from the bottom space 43, below the baffle 40, and is caused to flow in vertically moving temperature-buffering streams 45 outside of the baffle 40, in the spaces between the baffle and the four side-walls of the furnace-housing 10. These buffering streams 45 thus act as heat-buffers between the outside wall-surfaces of the hot tubular heat-insulated baffle 40 and the inside wall-surfaces of the relatively cool heat-insulated furnace-housing 10. It is not practical to hold the temperature of these buffering streams 45 constant within anything approaching the narrow limits which are required of the temperature-soaking space inside of the baffle 40, but the provision of these heat-buffering streams 45 makes it practically feasible to maintain the required extremely close temperature-tolerances for the soaking-temperature of the strip 15.

25 It is usually desirable for the temperature-soaking streams 41 of the constant-temperature gas to flow at a much more moderate rate than the rate of flow in the heating-passageway 30. This is because of the desirability of heating the strip to the desired soaking-temperature as quickly, or in as short a length of strip, as is reasonably possible, in order to keep the size of the furnace within reasonable limits. The slower gas-flow velocities are obtained in the temperature-soaking streams 41 by reason of the fact that the cross-sectional areas of said temperature-soaking streams are greater than the cross-sectional areas of the heating-streams 34 within the narrow heating-passageway 30.

30 The various passages and gas-flow spaces are designed so that the proper distribution of gas-flow takes place within the insulated baffle 40, as above described. It is

generally desirable to provide various dampers 48 by which the division of the gas-flow streams may be more accurately controlled or regulated.

The circulated gas is withdrawn from the furnace at any convenient point, preferably at some point outside of the tubular baffle 40. In the form of embodiment of the invention which is shown in Fig. 2, this exit-point for the circulated gas is provided at a point, in the furnace-housing 10, which is a small distance below the inlet-duct 32, as indicated by the outlet-duct 52. The gas which is withdrawn from the furnace through the outlet-duct or ducts 52 passes first through a heater-section or sections 53, and next through a blower or blowers 54, from which the gas is discharged to the previously mentioned inlet-duct 32, through which the gas is recirculated through the furnace. The heater-section 53 is shown, in Fig. 2, as comprising a plurality of fuel-consuming burners 55 which discharge their combustion-gases into the gas-recirculating system for heating the recirculated gas of the furnace. It will be understood, of course, that, in the broader aspects of our invention, any other form of heating-means may be used for heating the recirculated gas.

As shown in Fig. 2, we also provide an exhaust-duct 56 which leads off from the outlet end of the blower 54, having a damper 57 which may be opened wide for purging-purposes, when first starting up the furnace, so as to exhaust any gas which may be trapped within the furnace.

In the form of furnace which is shown in Figs. 1 and 2, the heat-treated strip, which leaves the furnace through the egress-slit 14, passes immediately into a quenching means, which is shown as comprising a plurality of water-spray nozzles 58 and a water-quench tank 59.

Depending from the bottom of the furnace-housing 10, and enclosing the egressing strip 15, we preferably provide a substantially gas-tight duct 61, the lower end of which is immersed within the water in the quench-tank 59, thus providing an exhaust-chamber which hermetically joins the quench-tank 59 to the bottom of the furnace-housing 10. We also preferably provide a means for exhausting the space in this exhaust-chamber above the quench-tank, as by means of an exhaust-pipe 62 (Fig. 2), from which gas is gently exhausted by means of an exhaust-blower 63. The rate at which gas is exhausted can be suitably adjusted by many convenient means, as by means of a large exhaust-damper 64 (Fig. 2), which bypasses a small exhaust-damper 65. The larger exhaust-damper 64 will usually be open during the initial heating-up period of the furnace; but once the furnace has been suitably heated, this large exhaust-damper 64 will normally be closed, and the small exhaust-damper 65 will be open or partially open.

The exhaust-blower 63 provides a slight suction for withdrawing steam from the exhaust-chamber over the quench-tank 59, thus preventing said steam from entering the furnace. At the same time, the exhaust-blower 63 gently exhausts the gas-space within the furnace, for providing an exit for the gaseous-combustion products of the burners 55, and also for controlling or limiting the amount of gas-movement into or out of the furnace at the point of strip-entry 13, thus combatting a slight tendency for hot gas to leak out of the furnace at the entry-slit 13, in the particular furnace-design which is shown in Figs. 1 and 2.

It will be understood, of course, that our furnace can be embodied in a large variety of designs. For example, as shown in Fig. 6, the strip 15 may enter at the bottom of the furnace-housing 10, through an entry-slit 73 and sealing rolls 74. Also, a large number of vertical passes of the strip may be used in the furnace. Thus, twelve strip-passes may be used, and the entire first two passes may be used for strip-heating, while the last ten passes are used for strip-soaking. It will be noted, in the form of invention shown in Figs. 6 and 7, that the hot-gas inlet-duct 32 is provided so as to feed into two plenum chambers 33A and 33B at the tops of the first two passes, re-

spectively, so that the strip-heating streams of longitudinally moving gas will flow downwardly along the opposite surfaces of the strip, at each of these first two passes, so that the gas flows counter to the movement of the strip in the first pass, and in the same direction as the movement of the strip in the second pass. The rate of longitudinal gas-flow of the strip-heating gases, in the narrow heating-passageways 30A and 30B in Fig. 6, is so many times greater than the rate of movement of the strip, that it makes relatively little difference whether the gas-flow is with, or counter to, the direction of movement of the strip.

In Fig. 6, also, all of the gas from the plenum chambers 33A and 33B flows downwardly in equal strip-heating streams along the opposite surfaces of the respective passes of the strip 15. The effect of lateral converging streams or gas-movements 36 is obtained, in Fig. 6, by means of Venturi surfaces or louvers 79 which are provided in the side-walls of the narrow heating-passageways 30A and 30B.

Other innovations are also illustrated in Figs. 6 and 7, including the use of diagrammatically indicated radiant tube heaters or electric resistance heaters 85, in place of the gas burners 55, and the omission of the pivoted roller-supporting arms 19, the quenching-means 58-59, and other parts which were shown in Figs. 1 and 2.

We wish it to be understood that the foregoing and many other changes may be made, in the way of the substitution of equivalents, the omission of unneeded parts, or the addition of various supplementary or auxiliary parts, including pressure and temperature regulators and gauges, air-filters, and many other practical details which will be readily understood by those skilled in the art.

We claim as our invention:

- 35 1. A heat-treating furnace comprising a thermally insulated furnace housing, means for guiding a strip to be treated to move longitudinally in a vertical direction through the furnace housing, a thermally insulated baffle surrounding the strip within the furnace housing, means for introducing gas to flow through the baffle and from the baffle through the space between the baffle and the furnace housing, and means for controlling the flow of gas to the space between the baffle and the furnace housing to maintain the strip at a desired temperature within the baffle.
- 40 2. A heat-treating furnace comprising a thermally insulated furnace housing, means for guiding a strip to be treated to move longitudinally in a vertical direction through the furnace housing, a thermally insulated baffle surrounding the strip within the furnace housing, an elongated vertical heat-exchange passage through which the strip passes, means for directing streams of gas through said passage on opposite sides of the strip in heat-exchange relation with the strip, said gas discharging from the passage to flow through the baffle and from the baffle through the space between the baffle and the furnace housing, and means for controlling the flow of gas to the space between the baffle and the furnace housing to maintain the strip at a desired temperature within the baffle.
- 45 3. A heat treating furnace comprising a thermally insulated furnace housing, means for guiding a strip to be treated to move longitudinally through the furnace housing in a plurality of vertical passes, a thermally insulated baffle surrounding the strip within the furnace housing, means for introducing gas to flow downward through the baffle and back upward through the baffle and through the space between the baffle and the furnace housing, and means for controlling the division of said upward flowing gas between the baffle and said space to maintain the strip at a desired temperature within the baffle.
- 50 4. A heat-treating furnace comprising a thermally insulated furnace housing, means for guiding a strip to be treated to move longitudinally through the furnace housing in a plurality of vertical passes, a thermally insulated baffle surrounding the strip within the furnace housing, an elongated vertical heat-exchange passage through which
- 55
- 60
- 65
- 70
- 75

an initial portion of the strip passes, means for directing streams of gas through said passage on opposite sides of the strip in heat-exchange relation with the strip, said gas discharging from the passage into said baffle to flow downward through the baffle and back upward through the baffle and through the space between the baffle and the furnace housing, and means for controlling the division of said upward flowing gas between the baffle and said space to maintain the strip at a desired temperature within the baffle.

5. A heat-treating furnace comprising a thermally insulated furnace housing, means for guiding a strip to be treated to move longitudinally through the furnace housing in a plurality of vertical passes, a thermally insulated baffle surrounding the strip within the furnace housing, an elongated vertical heat-exchange passage through which an initial portion of the strip passes, means for directing streams of gas through said passage on opposite sides of the strip in heat-exchange relation with the strip, means for directing substantially equal and oppositely directed streams of gas against opposite sides of the strip within the passage, all of said gas discharging into said baffle to flow downward through the baffle and back upward through the baffle and through the space between the baffle and the furnace housing, and means for controlling the division of said upward flowing gas between the baffle and said space to maintain the strip at a desired temperature within the baffle.

6. A heat-insulated chamber having a housing which has slits for the entry and egress of a strip and which is otherwise substantially gas-tight; an open-ended tubular heat-insulated baffle disposed in a substantially vertical position within said housing in closely spaced relation to the side walls of the housing; a means for guiding a longitudinally moving strip in at least one long substantially unsupported vertical span within said baffle; at least one narrow elongated vertically disposed heat-exchanging passageway surrounding the initial portions of the entire length of the strip within said chamber, the walls of the passageway being closely spaced from the side surfaces and the edges of the strip; a means for maintaining a supply of a gas at a temperature other than the entrance-temperature of said strip and for causing two substantially equal heat-exchanging streams of said gas to flow longitudinally along the respective surfaces of said strip in said passageway; the velocity of said heat-exchanging streams of gas, the length of the unsupported span of the strip, and the uneven warpings of the strip being in combination great enough to tend to cause a deleterious amount of decentering of said strip as it moves through said passageway; a means for superimposing, on the respective longitudinally moving heat-exchanging streams, a plurality of lateral converging movements of said gas, impinging upon the opposite surfaces of the strip, whereby to provide strip-centering forces within said passageway; and a means for guiding the exit-gas which leaves the passageway or pas-

sageways, so that most of said exit-gas travels longitudinally in slower-moving temperature-soaking streams on opposite sides of the remaining portions of the entire length of the strip within the chamber, and so that a portion of said exit-gas flows in vertically moving temperature-buffering streams outside of said baffle in the spaces between the baffle and the side-walls of the housing, the cross-sectional areas of said temperature-soaking streams being greater than the cross-sectional areas of said heat-exchanging streams, and the division of flow of said exit-gas between said temperature-soaking streams and said temperature-buffering streams being such as to maintain the temperature of the aforesaid remaining portions of the strip within desirably narrow limits as the strip continues its movement through the chamber.

7. A heat-insulated chamber having a housing with a temperature-holding space therein, said housing having slits for the entry and egress of a strip and being otherwise substantially gas-tight; an open-ended tubular heat-insulated baffle disposed in a substantially vertical position within said housing in closely spaced relation to the side walls of the housing; a means for guiding a longitudinally moving strip in at least one long substantially unsupported vertical span within said baffle, said strip entering said temperature-holding space at an entrance-temperature other than the ambient atmosphere outside of said chamber; a means for maintaining a supply of a gas at substantially said entrance-temperature of the strip; and a means for guiding said gas so that most of said gas travels longitudinally in temperature-soaking streams on opposite sides of the strip in said temperature-holding space, and so that a portion of said gas flows in vertically moving temperature-buffering streams outside of said baffle in the spaces between the baffle and the side-walls of the housing, the division of said gas between said temperature-soaking streams and said temperature-buffering streams being such as to maintain the temperature of the strip within desirably narrow limits as the strip moves through the temperature-holding space.
